Primary Examiner — Ricky Pham(74) *Attorney, Agent, or Firm* — Kile Park Reed & Houtteman PLLC(57) **CLAIM**

I claim, the ornamental design for a cooking pan, as shown and described.

DESCRIPTION

FIG. 1 is a top and front perspective view of a cooking pan, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an exploded reference perspective view showing how the cooking pan is placed on a heating cooker in the arrow direction.

The broken lines in FIG. 8 are shown for the purpose of illustrating parts of the heating cooker that form no part of the claim.
